(57) **CLAIM**

The ornamental design for a shoe, as shown and described.

DESCRIPTION

FIG. 1 is a front perspective view of a shoe showing my new design;

FIG. 2 is a front view thereof;

FIG. 3 is an opposite side front perspective view thereof; and,

FIG. 4 is a top view thereof.

The broken line immediately adjacent to the shaded area defines the bounds of the claimed design and forms no part thereof. The small unshaded areas inside the circles and star-shaped regions form no part of the claimed design. The broken lines depicting the remainder of the shoe form no part of the claimed design.
